John R. Peters

UNITED STATES PATENT OFFICE.

JOHN R. PETERS, OF NEW YORK, N. Y.

IMPROVEMENT IN AIR-ENGINES.

Specification forming part of Letters Patent No. 36,961, dated November 18, 1862.

To all whom it may concern:

Be it known that I, JOHN R. PETERS, of the city, county, and State of New York, have invented a new and useful Improvement in Air-Engines; and I do hereby declare that the following is a full, clear, and exact description of the same, reference being had to the accompanying drawings, forming part of this specification, in which—

Figure 1 is a vertical section of an engine with my improvement, the plane of section passing through the air-heating vessels. Fig. 2 is a plan of the same. Fig. 3 is a central section of one of the stuffing-boxes. Fig. 4 is a vertical section exhibiting the heaters with their plungers in a position different from those shown in Fig. 1.

Similar letters of reference indicate corresponding parts in the several figures.

The first part of this invention relates to that class of air-engines (known as "Stirling's") in which the air is heated in two vessels connected with opposite ends of the working-cylinder, by being transferred from one end to the other of the said vessels alternately by means of plungers working therein, the working-cylinder being double-acting.

In such engines, as heretofore constructed, the aforesaid plungers have been so connected that one always ascended while the other descended, and vice versa, and the time occupied by the stroke of each has been generally equal to that occupied by the stroke of the working-piston, and the consequence has been that the pressure of the air has been made effective upon the working-piston through but a portion of each stroke.

The object of this part of the invention is to render the said pressure effective throughout the whole stroke of the working-piston; and to this end it consists in so operating the two plungers that the one in either heating-vessel is stationary in its uppermost position with the space below it full of heated air, while the working-piston is making the stroke from the end of the cylinder in connection with that vessel, the plunger in the other heating-vessel (which is shut off from the cylinder) making both its upward and downward stroke in the meantime, and causing the latter vessel to be filled with heated air to produce the return-stroke of the working-piston,

by which means a more uniform and greater power is caused to be developed in the operation of the engine, and its working is effected with greater economy.

To reduce as much as possible the size of the engine, I propose, generally, to use air mechanically compressed to a tension much greater than that of the atmosphere, and to do this economically I use the same air over and over again. The power of engines in which the air is used in this way depends upon the difference of temperature of the air at the top and bottom of the heating-vessel. The air when at the top of the heating-vessel is intended to be cooled either by circulating water through pipes inside or by inclosing the upper part of the vessel with a jacket, through which water is to be made to circulate.

The remaining part of my invention consists in an improvement in the packing of the stuffing-boxes through which the rods of the plungers of the heating-vessel work, applicable also to other stuffing-boxes, for the purpose of making the oil or other lubricating material employed therein serve in a novel manner to aid in preventing leakage.

To enable others skilled in the art to make and use my invention, I will proceed to describe its construction and operation.

A is the working-cylinder, fitted with slide or other valves, like those used in a steam-engine, for the induction and eduction of the air, a separate induction-valve being employed for each end of the cylinder, working in a separate valve-chest.

b b' are the valve-chests. The valves are to be operated by an eccentric, tappets, or other suitable means. A single valve-chest and valve may, however, be used if check-valves opening toward such valve-chest be applied in the pipes g g'.

B B' are the two heating-vessels, and P the furnace in which their lower parts are received to heat the air below the plungers CC', which are made of great depth and filled with non-conducting material, and their exteriors are so much smaller than the interiors of the vessels B B' as to leave a narrow air-passage between them, as shown in Fig. 1. These vessels are connected by separate pipes g g' with the valve-chests b b' of the working-cylinder—one with each chest—the said pipes

communicating with the said vessels below their plungers. The plungers C C' are furnished with rods c c', working through stuffing-boxes in the covers of the vessels B B', and the said rods are attached to separate levers D D', arranged to work on fixed fulcrums d d' in standards E E', which are secured on the top of the vessels B B'. These levers have applied to them springs F F', of sufficient strength to raise the said levers and draw the plungers C C' up to the tops of the vessels B B'.

G is a rock-shaft working in suitable bearings in standards H H, arranged between the vessels B B'. This shaft carries two toes, I I', for operating on the two levers D D', and an arm, J, which is connected by a rod, L, with an additional crank, K, on the crank-shaft M of the engine, for the purpose of producing the oscillation of the said rock-shaft by the revolution of the crank-shaft, the two toes and the arm J being so arranged that when the working-piston in the cylinder A is at either end of its stroke the toes occupy the central position shown in Fig. 4, and do not depress either of the levers D D', and consequently leave both the plungers C C' at the tops of the vessels B B'; but that during the stroke of the piston toward either end of the working-cylinder the plunger in the vessel B or B' next to and in connection with that end of the cylinder is depressed by the action of its respective toe and allowed to rise again, the downward and upward stroke of the plunger being completed during the one stroke of the piston, and the other plunger being in the meantime stationary in its highest position.

In Fig. 1 the plungers are shown in the position they respectively occupy when the working-piston is at the middle of the stroke to the right, and in red outline in the position they respectively occupy when the said piston is at the middle of its stroke to the left. By this mode of operating the plungers the transfer of the hot air left in the hot lower part of each heating-vessel, after a stroke of the working-piston has been produced by air from that vessel to the cold upper part thereof, and the transfer of cool air to the lower part of the vessel to be heated, are both completed during the time that the other vessel is supplying the cylinder, and the consequence is that each heating-vessel remains full of hot air during the whole of that stroke of the piston for which it supplies the air, and the effect of the expansion of the air is continued upon the piston throughout its whole stroke, subject, of course, to the gradual diminution of pressure in the heating-vessel consequent upon the expansion as the stroke proceeds.

Instead of employing springs F F' to raise the plungers C C', the plunger-rods c c' may be made so large that the pressure of air under the plungers may overcome the weight of the plungers and the friction of the stuffing-boxes, and produce the upward movement of the plungers in the same manner as the springs do

after they have been forced down by the toes of the rock-shaft; or it may be understood by engineers that a similar movement of the plungers may be effected by entirely different means.

S is a compressing-pump having its piston connected with the working-piston of the engine, to be thereby operated for the purpose of compressing air to be supplied through a pipe, N, with the branches e e' to the upper parts of the two vessels B B' or through a pipe, N', to the reservoir or cooler R. This pump is only required to be set in operation on the starting of the engine to get up the desired pressure and occasionally to make up for any escape by leakage, and at all other times the said pipe N is shut off from the pump by a cock, h, and a cock, i, is opened to make the piston of the pump work constantly in equilibrio. If the cooling-vessel R, which constitutes the second part of my invention, were not used, the pipe N would have a direct connection with the upper parts of the heating-vessels B B'; but when the cooler is used, as represented in the drawings, to cool the exhausted air previously to its return to the upper parts of the heating-vessels B B', the said pipe is connected by a pipe, N', with the lower part of the said cooler, and the upper part of the latter is connected with the exhaust-pipe Q. The cooling-vessel R cools air by presenting a large surface to the surrounding atmosphere; or it may be cooled by water. The air entering it at the top and leaving it at the bottom causes the coolest portion of its contents to be always supplied, as those portions settle toward the bottom by a natural law.

To use this cooling-vessel successfully, the working-cylinder requires to be fitted, like the cylinder of a steam-engine, with induction and eduction valves, and the pipes c c' require to be fitted with check-valves closing in an outward direction from the heating-vessels, which is contrary to the practice of Stirling, who used no valves between the working-cylinder and the heating-vessel. Without such valves it would be objectionable to have any more space than is absolutely necessary between the cylinder and the heating-vessels, as a loss of power would be consequent upon the expansion of the air into any such space.

The cooling-vessel represented is a simple cylinder cooled from the contact of its exterior by the atmosphere; but it may be constructed of a series of pipes running through it, to be cooled also by the circulation of water or of the atmosphere through such pipes; or instead of such a vessel, a cooler may be made of a coil of pipe exposed to the atmosphere. The object of this cooler may be likened to that of the condenser of a steam-engine, and is precisely the reverse of what has been known as a "regenerator," which has been applied to air-engines.

If it should be desired to take the air into the heaters at the pressure of the atmosphere and to exhaust from the working-cylinder

into the atmosphere, the cooling vessel or cooler R is of course unnecessary, and in such case the pipes e e' will be cut off near the heating-vessels, outside of the check-valves before mentioned. If desirable, the exhaust air may also be allowed to pass back from the working-cylinder into the heating-vessels through the same pipes which supply the working-cylinder. In this case, when the air passes back from the working-cylinder to the heating-vessels, the slide-valve of the cylinder will operate as a check-valve, and will rise to allow the air to pass back. A sufficient chamber or space, representing what may be termed an "exhaust-passage," should be left under the slide-valve to afford room for the compression of any exhaust air that remains at the end of the working-cylinder when the piston nears the end of its stroke. In case the cooler is dispensed with the upper part of the cylinder may be cooled by the application thereto of water, in accordance with the plan of Stirling or others hereinbefore mentioned.

The cooler R can be used as a reservoir for compressed air, which can be held in readiness to supply the engine when increased power is temporarily wanted, in which case the engine may exhaust directly into the atmosphere. This reservoir of compressed air would also be found useful in compensating the engine for any loss of its air by leakage.

My improved stuffing-box is best illustrated in Fig. 3, which represents it on a larger scale than the other figures. The gland T, which is used to compress the packing k, as in any oth-

er stuffing-box, is made with a deep cut, l, in its upper part for the reception of oil or other lubricating material, and around the upper edge of this cup a leather collar, n, is secured by a clamping plate or ring, m, which is held by the same screw-bolts o o and nuts p p as are employed for securing the gland down upon the packing. The leather collar n is so constructed as to hug the plunger-rod c closely, and to be made to hug it the tighter by any pressure on its under side, like what is known as "water-packing." Any air passing the packing k forces the oil or melted lubricating material against the collar n, and so causes it to hug the rod in such a manner as to prevent the air from escaping. The lubricating material thus applied, in combination with the leather collar, serves to prevent the said collar from being dried up by the heat and to keep the said collar soft and pliable.

I do not confine myself to the use of the within-described mechanical means of producing the movement of the plungers, as various means may be employed to produce the same movement; but

What I claim as my invention, and desire to secure by Letters Patent, is—

The construction of the stuffing-box gland with an oil-cup, l, and flexible collar n, combined substantially as herein described, for the purpose set forth.

JOHN R. PETERS.
